Inventor:

R. W. Green

UNITED STATES PATENT OFFICE.

R. W. GREEN, OF BRADFORD, PENNSYLVANIA.

IMPROVEMENT IN DUMPING-WAGONS.

Specification forming part of Letters Patent No. 39,478, dated August 11, 1863.

To all whom it may concern:

Be it known that I, R. W. GREEN, of Bradford, in the county of McKean and State of Pennsylvania, have invented a new and Improved Dumping-Wagon; and I do hereby declare the following to be a full and exact description of the same, reference being had to the accompanying drawings, making part of this specification, in which—

Figure 1 is a side elevation of my improved device. Fig. 2 is a vertical transverse section of the same.

Similar letters of reference indicate corresponding parts in the two figures.

The subject of this invention is a wagon or vehicle wherein dirt, gravel, sand, &c., may be conveyed, and from which the same may be quickly and readily discharged.

The invention consists, essentially, in the combination of a peculiarly-constructed dirt-receptacle, with chains working upon a windlass, to which rotation is imparted through the medium of suitable gearing, all as will be hereinafter explained.

To enable others skilled in the art to which my invention appertains to fully understand and use the same, I will proceed to describe its construction and operation.

B B in the accompanying drawings represent the front and hinder pieces, respectively, of the framing of the wagon, and Q Q the side pieces. To the inner sides of the pieces Q Q are attached vertical bolsters A A, the purpose of which is to provide means for the attachment of cross-pieces or beams R R. To the under side of these beams it is designed to attach in any suitable manner the truck of an ordinary farm-wagon. Within the framing thus formed is suspended or pivoted the dumper or receptacle for the gravel, sand, &c. This dumper is formed in two curved or circular pieces, J J, the upper ends of which, when the dumper is in its normal or closed position, will be flush with the tops of the side pieces, Q Q. Each division of the dumper is provided at its respective ends with a metallic frame, K K, upon the end of which is formed a pivot, L, journaled in a metallic box, P, rigidly fastened to the front and hinder pieces of the framing of the wagon in any suitable manner. The pieces J J

have hinged or jointed to their lower end a section or piece, M, which, when the dumper is in position for the conveyance of a load, constitute a perfectly level floor, whereby the dumper is rendered less liable to be forced open by the pressure of its contents than were the curve of each of the divisions J J extended to the lower terminus thereof.

G G are braces which serve to impart additional strength to the framing of the wagon.

n n represent metallic bands or braces secured to the outside of the pieces J J to impart strength thereto.

C is the driver's seat, within which is journaled a transverse windlass or shaft, E. Upon and near each end of the shaft E, and within the inclosure C, a chain or rope, F, is securely fastened. At their opposite ends the chains F F are attached, respectively, near the lower edges of the divisions J J of the dumper.

D' is a gear-wheel keyed on the outer end of the windlass E and working into a pinion, D, on a short shaft, which is journaled in the seat C and rotated by means of a crank, H.

I is a step for the feet of the driver.

When in their closed position, the divisions J J may be thus retained by a transverse rod or bar, R, held in the desired position by a button, R'.

The operation will be understood from the foregoing description.

The dumper may be opened to discharge its contents by turning the crank H in either direction.

Owing to the peculiar form and arrangement of the dumper and the devices for suspending or sustaining the same, very little power will be required to turn the crank, and hence the dumping operation may be performed with as great celerity as may be desirable.

The pieces J J may be so arranged as that the force of gravitation will be sufficient to cause them to resume their closed position, or this may be effected in any other desired way.

I am aware that it is common to construct dumping-wagons with movable bottoms, and also that the gearing D D' and windlass and

chains E F F are old devices, and I do not wish to be understood as claiming either of these devices, broadly; but,

Having thus described my invention, what I claim as new therein, and desire to secure by Letters Patent, is—

The box or body of the dumper, constructed with circular sides J J and hinged sections M

M, in combination with the pivoted frames K K, all arranged and operating substantially as and for the purposes specified.

R. W. GREEN.

In presence of—

A. K. JOHNSON,
S. WALKER.
